UNITED STATES PATENT OFFICE.

JOHN GEORGE LEYNER, OF DENVER, COLORADO.

ROCK-DRILLING SYSTEM.

SPECIFICATION forming part of Letters Patent No. 739,551, dated September 22, 1903.

Application filed October 1, 1902. Serial No. 125,538. (No model.)

To all whom it may concern:

Be it known that I, JOHN GEORGE LEYNER, a citizen of the United States of America, residing at Denver, in the county of Arapahoe 5 and State of Colorado, have invented certain new and useful Improvements in Rock-Drilling Systems; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to a new combination of machine elements, which through the medium of compressed air and water, for drilling rock in mines; and the objects of my invention are, first, to provide means for conveying air and water in an operative form through pipes and through an operative rock-drilling engine to the bottoms of holes in rock while drilling them; second, to actuate the rock-drill and eject the rock-cuttings from 20 the holes in rock while drilling them. I attain these objects by the mechanism illustrated in the accompanying drawings, in which—

25 Figure 1 represents a perspective view of a system of rock-drilling machinery embodying my invention, and Fig. 2 represents a section through a rock-drill and its storage-tank system.

30 Similar characters of reference refer to similar parts throughout both views.

Referring to the drawings, the numeral 1 designates an operative air-compressor engine; 2, an air-receiving tank or reservoir.

35 3 designates an operative rock-drilling engine, of any suitable type, but more especially like the type shown in United States Patent No. 709,022, issued to me September 16, 1902, application Serial No. 68,808, filed by me July 18, 1901, which type of rock-drilling engine 40 is particularly adapted to the use of both air and water in drilling holes in rock.

45 4 designates a portable water-storage tank, which is connected to the rock-drilling engine by a hose 5. One end of the hose 5 is connected to one side of the tank 4, and to the opposite side of the top of the tank one end 50 of a hose 6 is connected. The opposite end

of the hose 6 is connected to a T 6^A, which is inserted in the air-supply pipe 7. The air-supply pipe 7 extends from the air-receiver 2 55 into the workings of the mine. A valve 8 is placed in the hose 6, and a valve 9 is preferably placed in the air-pipe 7. A hose 7^A extends from the T 6^A to the valve of the rock-drilling engine. The air-receiving tank is 60 connected by a pipe 10 with the air-compressor, and a valve 11 is inserted in the pipe 10. The portable water-tank 4 is a small iron tank, preferably of about eighteen gallons capacity. Its top is provided with a water-inlet aperture 12, which is closed by a cap 12^A, which is threaded to a projecting nipple 13, that is formed on top of the tank.

65 The hose 5 is connected in any suitable manner to one end of a pipe 14, that projects 70 above the tank (see Fig. 3) and depends into the tank, its lower end being positioned close to the bottom of the tank in order to practically empty the tank.

75 The hose 6 is secured in any suitable manner to a short nipple 15, that is secured in the top of the tank and extends simply through it.

80 The rock-drilling engine may be in all respects like the type of compressed-air rock-drilling engines in common use, except that it is arranged and adapted to convey a stream of water through it. I preferably use a rock-drilling engine designed as shown in Fig. 2, consisting of the cylinder 16, front cylinder-head 17, rear cylinder-head 18, supplementary cylinder-head 19, a piston 20, which is provided with a ram portion 31, that extends into the front cylinder-head, the peripheral surface of which is provided with flutes 32, that slide loosely in a nut 33, which is threaded to a chuck 34, that fits into the front cylinder-head 17, a feed-screw 21, and supporting-shell 22, and a drill-bit 23, and a suitable valve mechanism 24. The drill-bit is removable mounted in the front cylinder-head. The 85 drill-bit 23 contains an axial bore through it from end to end. This axial bore is preferably made in two diameters 25 and 25^A, the larger being at the hammer-striking end of the drill-bit and the smaller at the rock-cutting end of 90 the drill, the two apertures intersecting each other within the drill-bit, which is operatively supported in the front cylinder-head 17 of the drilling-engine in the clutch 34. The water-

95 100

hose 5 is connected to a coupling 25, that is supported by a supplementary cylinder-head 19, that is secured to the main cylinder-head. This coupling communicates, by means of a 5 passage 26, with an axial bore 27, formed in the supplementary cylinder-head 19. A valve 28 is arranged in the coupling 25 of the supplementary cylinder-head and controls the passage 26. A tube 24^A is secured in the inner end of the supplementary cylinder-head and extends loosely through an axial aperture 30 in the piston 20 of the drill and extends loosely into the larger axial hole in the drill-bit.

15 The above-described arrangement of the water-passage through the rock-drilling engine is the preferred construction; but a suitable passage could be made through another part of the drilling-engine or along the side 20 of it and along the side of the drill-bit or through the side of the drill-bit. I do not illustrate these several arrangements, as the arrangement shown is much preferred to any other. The valve and piston actuating mechanism is substantially similar to that of rock-drilling engines in common use.

The operation of my system is as follows: An air-compressor and an air-receiver or air-reservoir tank is placed at the entrance to 30 the mine, as shown in Fig. 1, and an air-supply pipe is extended into the workings of the mine to points near to where rock-drilling work is to be done. The rock-drilling engine is then set up in an operative position to drill 35 rock, and its valve mechanism is connected by a hose 7^A to the air-supply pipe, which leads to the air-receiver. The water-coupling of the rock-drill is then connected to one end of a hose 5, which leads and is connected at its opposite end to the portable water-storage tank. This hose 5 is connected to the pipe 14, that extends close to the bottom of the tank. The tank is then connected by the hose 6 and nipple 15 and the T 6^A with the air-supply 40 pipe 7 and by this pipe with the air receiver and compressor. Sufficient surplus length of hose is provided between the portable water-tank and the rock-drill to enable the tank to be placed in recesses in the side walls of the 45 mine's workings and to allow the tank to be moved around at will by attendants, which can be very easily done. The tank is filled with water by removing its cap 12^A. Air is compressed by the air-compressor into the air-receiver, where a suitable working pressure is maintained to effectually operate the rock-drilling engine at the end of the system. The air from the receiver flows direct to the valve mechanism of the rock-drilling engine and also 50 flows direct into the portable water-tank and forces the water therein out through the pipe 14 and hose 5 to the coupling of the rock-drilling engine and into and through its drill-bit to the bottom of the hole being drilled in 55 the rock A A. A portion of the compressed air in the forward end of the cylinder at each stroke of the piston passes through the flutes

of the ram of the piston and enters the drill-bit and mingles with the water and drives the water out of the drill-bit against the bottom of the hole being drilled in the rock, thus not only keeping the hole thoroughly wet, and thus making the rock easier to drill, but preventing the dust incidental to dry drilling, and also drives or blows out of the 75 hole as it is being drilled the rock-cuttings, which, above everything, is the essential object to be attained, as it entirely obviates the necessity of removing the drill-bit every few inches it drills into the rock to remove the 80 rock-cuttings manually with a spooning-tool, as is the common practice in drilling rock in other rock-drilling systems. The air mingling with the water at each stroke of the piston forces the water out of the drill-bit as 85 a fine spray in puff-like jets at each blow of the piston and of the drill-bit against the rock.

Having described my invention, what I claim as new, and desire to secure by Letters Patent, is—

1. In a rock-drilling system, the combination with an operative air-compressor, an air-receiving reservoir, an air-supply system, and the rock-cutting drill-bit, with a portable water-storage tank, connected to said air-supply system, an air-operating rock-drilling engine, operatively connected with said air-supply system, and operatively connected with said air-actuated portable water-storage tank, and means connected with said rock-drilling engine for mingling said air and water together and for conveying said commingled air and water to the cutting-point of said drill-bit, substantially as described.

2. In a rock-drilling system the combination with an operative compressed-air system, a portable water-storage tank containing a supply of water in connection with said air-supply system, and an operative rock-drilling engine operatively connected to said compressed-air system, and operatively connected to said portable water-storage tank to secure a stream of water therefrom, and means connected with said rock-drilling engine including a hollow drill-bit for commingling said air and water together and discharging said commingled air and water through said drill-bit to its rock-cutting point, substantially as described.

3. In a rock-drilling system, the combination with an operative air-compressor, an air receiver or reservoir, an air-supply system, and the rock-cutting drill-bit, of a compressed-air-actuated rock-drilling engine, operatively connected to said compressed-air supply-pipe system, and containing a water-passage to the cutting-point of its rock-cutting drill-bit, said water-passage being arranged to communicate with the compressed-air passages through said rock-drilling engine, a portable water-supply tank provided with a supply of water connected by a flexible tube or hose to the water-passage through said rock-drilling engine, and provided with a flexible tube or

hose connection with said compressed -air-supply system, and a water-inlet to said tank, whereby said compressed air actuates said rock-drilling engine, and forces water from 5 said tank through said rock-drilling engine, and said air and water is commingled together and discharged from said drill-bit into the bottom of the hole being drilled, substantially as described.

10 4. In a rock-drilling system, the combination with the air-compressor, the air-receiving reservoir and the distributing system of the portable water-storage tank operatively connected to said air-distributing system, a 15 rock-drilling engine provided with suitable ports or water-passages, operatively connected to said portable water-storage tank and to

said air-distributing system, a rock-cutting drill-bit removably secured to said drilling-engine, means for controlling the supply of 20 water and air flowing to said rock-drill, means including suitable air and water passages in said rock-drilling engine for mingling said water and air together, and for discharging said commingled air and water together from 25 the cutting-point of said drill-bit, substantially as described.

In testimony whereof I affix my signature in presence of two witnesses.

JOHN GEORGE LEYNER.
